CLAIM

The ornamental design for an electronic touch board, as shown and described.

DESCRIPTION

FIG. 1 is a perspective view of an electronic touch board according to our new design;

FIG. 2 is a front view thereof;

FIG. 3 is a rear view thereof;

FIG. 4 is a right, side view thereof;

FIG. 5 is a left, side view thereof;

FIG. 6 is a top plan view thereof; and,

FIG. 7 is a bottom plan view thereof.

The broken-lines in the drawings depict portions of the electronic touch board that form no part of the claimed design.

The shade lines indicate the character and contour of the surfaces represented, not to be confused with surface ornamentation.
